(57) **CLAIM**

The ornamental design for an expandable hose, as shown and described.

DESCRIPTION

FIG. 1 is a front, right and top perspective view of an expandable hose, showing our new design;

FIG. 2 is a front view thereof;

FIG. 3 is a rear view thereof;

FIG. 4 is a left view thereof;

FIG. 5 is a right side view thereof;

FIG. 6 is a top plan view thereof;

FIG. 7 is a bottom plan view thereof;

FIG. 8 is a perspective view in the using configuration thereof;

FIG. 9 is another perspective view in the using configuration thereof;

FIG. 10 is an enlarged exploded view of the pipe body of the expandable hose;

FIG. 11 is an enlarged exploded view of the pipe body shown in a state of use;

FIG. 12 is an enlarged cross sectional view of the expandable hose of FIG. 2 taken in the direction of line 12-12 in FIG. 2; and,

FIG. 13 is an enlarged cross sectional view of the expandable hose of FIG. 2 taken in the direction of line 13-13 in FIG. 2.

The evenly spaced broken lines illustrate portions of the expandable hose and environment that form no part of the claimed design. The long dash short dash broken lines shown in the figures depict boundaries of the claim and form no part thereof.

The expandable hose is shown with a symbolic break in its length. The appearance of any portion of the article beyond the break forms no part of the claim.
